UNITED STATES PATENT OFFICE.

IRWIN H. SPELMAN, OF CORTLAND, OHIO.

SAP-SPOUT.

SPECIFICATION forming part of Letters Patent No. 257,525, dated May 9, 1882.

Application filed October 8, 1881. (No model.)

To all whom it may concern:

Be it known that I, IRWIN H. SPELMAN, a citizen of the United States of America, residing at Cortland, in the county of Trumbull and State 5 of Ohio, have invented certain new and useful Improvements in Sap-Spouts; and I do hereby declare the following to be a full, clear, and exact description of the invention, such as will enable others skilled in the art to which it applies 10 to make and use the same, reference being had to the accompanying drawings, and to letters or figures of reference marked thereon, which form a part of this specification.

This invention has relation to improvements 15 in that class of devices known as "sap-spoons;" and it consists in the novel construction and arrangement of a spur or strip applied to the tube and a part of the same, whereby more strength is given to the spout, and thereby 20 preventing the same from any injury when driven into a tree, as will be more fully explained hereinafter.

The annexed drawings, to which reference is made, fully illustrate my invention, in which— 25 Figure 1 represents a view of a tree having my improved sap-spoon attached. Fig. 2 represents a side view of the spout. Fig. 3 represents an end view of the same. Fig. 4 represents a view of the spout detached from the 30 spur or strip. Fig. 5 represents a side view of the spur or strip detached from the spout. Fig. 6 represents a side view of the hook to which the bucket is attached, and Fig. 7 is an end view of the same.

35 The letter A designates a sap-spoon, constructed of sheet metal and of tapering form, having a groove, a, that extends from the smaller end a' of the spout to a short distance from the opposite end thereof.

40 Within the slot or groove a is placed a metal spur or strip, B, which has on its upper edge

a projection, b, and on the under side thereof is formed a shoulder, b', that fits in slot b², made in the smaller end of the spout.

C designates a hook by which a pail or bucket 45 may be suspended in catching the sap, and it is constructed of flat metal or cast-iron, and is provided with an eye, c, that is tapering in order to correspond with the shape of the spout, on which it is hung. Said hook and eye c are 50 formed of one piece and bent in the form shown in Figs. 6 and 7 of the drawings.

It will thus be seen by the above description that I construct a sap-spoon with a metal spur or strip running lengthwise and within 55 the same, and said spur, being soldered or otherwise firmly secured to the spout, serves to strengthen and prevent injury to said spout when the latter is driven into a tree.

It will further be observed that by constructing a hook as herein shown and described the same has a broad bearing upon the spout, thereby preventing backward and forward movement, and is not liable to get out of place. Said hook may be made stationary to the spout, 60 if desired.

Having thus described my invention, what I claim, and desire to secure by Letters Patent, is—

The combination, with the sap-spoon A, constructed as described, of the spur B, constructed of a flat piece of metal, and having a shoulder, b', to engage with the notch b² on the end of the spout A, as herein described, and for the purpose set forth.

In testimony whereof I affix my signature in presence of two witnesses.

IRWIN H. SPELMAN.
